UNITED STATES PATENT OFFICE.

HARRY E. McLAIN, OF PITTSBURGH, PENNSYLVANIA, ASSIGNOR OF ONE-FOURTH TO
WILLIAM BROAD, OF BEAVER FALLS, PENNSYLVANIA.

APPARATUS FOR MASSAGE TREATMENT.

1,234,700.

Specification of Letters Patent.

Patented July 24, 1917.

Application filed May 1, 1917. Serial No. 165,681.

To all whom it may concern:

Be it known that I, HARRY E. McLAIN, residing at Pittsburgh, in the county of Allegheny and State of Pennsylvania, a citizen 5 of the United States, have invented or discovered certain new and useful Improvements in Apparatus for Massage Treatment, of which improvements the following is a specification.

10 My invention relates to apparatus for giving massage treatment to a relatively large portion of the body, as for the reduction of obesity, relief of rheumatism, etc.

In giving such treatments the most benefit is derived when the portion of the body being treated is heated, a result which cannot be obtained by the apparatus usually employed for the purpose, because in such apparatus the massaging movements are 20 effected by various forms of members which are operated manually or by mechanical power.

It is accordingly the object of my invention to provide a massaging apparatus 25 which will simultaneously massage, and locally heat, the portion of the body being treated.

In the accompanying sheet of drawings, which form part of my specification, I have 30 illustrated the preferred embodiment of my invention. Figure 1 is a plan view of the apparatus embodied in a belt; Fig. 2 a face view of a portion of the apparatus, the plane of view being indicated by the line II—II, 35 Fig. 1; Fig. 3 a face view of the apparatus embodied in a pad; Fig. 4 a sectional view of a massage vibrator forming a part of the apparatus, the plane of view being indicated by the line IV—IV, Fig. 5; and Fig. 5 a 40 sectional view taken on the line V—V, Fig. 4.

In the practice of my invention I mount upon a belt, pad, or other suitable flexible support, a plurality of electro-magnetic 45 massage vibrators adapted to vibrate in directions perpendicular to such support. By electro-magnetic massage vibrator, I mean that type of vibrators wherein the vibration of the movable member is effected by means 50 of an electro-magnet contained in the vibrator casing and adapted to be intermittently energized by an alternating current or a rapidly interrupted direct current. In operation, the electro-magnets of such vibrators

become heated and thus afford, at the point 55 of application of the massage treatment, the desired local heating of the patient.

While any desired form of electro-magnetic massage vibrator may be used, I preferably use the form illustrated herein, which 60 is compact in construction, light in weight, and otherwise well adapted for this particular use. As shown in Figs. 4 and 5, the vibrator comprises a shallow disk-shaped casing having a back or bottom 1, side wall 65 2 and a face or cover 3. The electro-magnet, which preferably consists of two spools 4 and a laminated core 5, is secured to the back 1 in such position that the axis of its windings are parallel to such back. The 70 movable element or member of the vibrator is a portion of the cover 3 which is made of resilient metal. The vibrating portion is set apart from the cover by means of a slit 6 which is preferably substantially semi- 75 circular in shape and extent. At the outer end of this vibrating portion there is attached an armature 7 which projects downwardly from the cover to a position adjacent to the end of the magnet. In operation, the 80 intermittent energization of the magnet has the effect of rapidly vibrating the slit portion of the cover.

In the apparatus shown in Figs. 1 and 2, a series of electro-magnetic vibrators of the 85 character just described are shown attached to a belt 8, as by means of suitable fastening clips 9 secured to the binding posts 10 of the vibrators, the bases of the vibrators being adjacent to the inner face of the belt, 90 and the faces lying substantially in a common plane. If desired, the belt may be provided with a suitable flap 14 of cloth or other thin material to cover the otherwise exposed faces of the vibrators. As indicated, the several vibrators are electrically 95 connected to conductors 11 so that all the vibrators may be operated to produce the desired simultaneous massage treatment and heating.

In case it is desired to treat a larger portion of the body, a larger number of the vibrators may be secured to a pad 12 as indicated in Fig. 3, and it will be understood that such pad may be variously shaped, depending upon the particular or specific requirements.

According to the provisions of the patent

statute, I have described the principle and operation of my invention, together with the construction which I now consider to represent the best embodiment thereof. However, 5 I desire to have it understood that the construction is only illustrative, and that my invention may be practised by other forms of construction than that particularly shown and described.

10 I claim as my invention:

1. An apparatus for giving massage treatment comprising a flexible supporting member and a plurality of electro-magnetic massage vibrators secured thereto and having 15 their vibrating elements lying substantially in a common plane, said vibrators being adapted to simultaneously massage and heat

the portion of the body to which the apparatus is applied.

2. In an apparatus for giving massage treatment, the combination of a flexible belt, and a plurality of electro-magnetic massage vibrators secured thereto, said vibrators having oppositely disposed substantially flat bases and vibrating faces, the bases being adjacent to said belt and the vibrating faces lying substantially in a common plane. 25

In testimony whereof I have hereunto set my hand.

HARRY E. McLAIN.
